UNITED STATES PATENT OFFICE.

WILHELM SCHAEFER, OF HAMBURG, GERMANY.

INCANDESCENT GAS-LAMP.

SPECIFICATION forming part of Letters Patent No. 726,765, dated April 28, 1903.

Application filed February 15, 1902. Serial No. 94,302. (No model.)

To all whom it may concern:

Be it known that I, WILHELM SCHAEFER, engineer, a subject of the German Emperor, residing at Kleine Bäckerstrasse 33, Hamburg, in the German Empire, have invented new and useful Improvements in and Relating to Incandescent Gas-Lamps, (for which I have made applications for patents in Austria, dated January 13, 1902; in Denmark, dated 10 January 14, 1902; in Norway, dated January 16, 1902; in Sweden, dated January 16, 1902; in Germany, dated January 18, 1902, design patent dated January 18, 1902; in France, dated January 21, 1902; in Belgium, dated 15 January 22, 1902; in Great Britain, dated January 22, 1902, and in Hungary dated January 27, 1902,) of which the following is a specification.

This invention relates to incandescent gas-lamps, and has for its object to provide apparatus for producing increased luminosity without its being necessary to resort to a forced gas-pressure and the accompanying long special feed-pipes for the creation of the increased draft; and it consists in the employment of Bunsen burners for illuminating incandescent mantles with a special form of lamp construction adapted to obtain the greatest possible illuminating effect.

30 The invention is illustrated in the accompanying drawings, in which—

Figure 1 is a sectional view showing the construction of the lamp. Fig. 2 is a plan view of the gallery supporting the chimney, and Fig. 3 shows the adjustable gas-nozzle forming part of the Bunsen burner.

The gas-supply pipes 1 and 2 support above the main gas-cock 3 the distributing-chamber 4, upon which are screwed the number of separate burners corresponding to the illuminating power of the whole lamp—three in this case—the special gas-regulating nozzle 5, hereinafter described, being interposed. A flange 6, projecting laterally from the tops of the 45 burners, supports the gallery 7, which is shown in plan in Fig. 2. The incandescent mantle-holder is arranged in the center of the burner. This holder consists of a metal rod 9 in a socket 8, the upper extremity of this 50 rod carrying a block 10, the position of which may be adjusted by means of a set-screw, (not here represented,) and from this block pro-

ject hooks 11, from which the incandescent mantles 12 are suspended. These mantles are inclosed by the chimney 13. The chimney is of such a form as to adapt it to the space occupied by the mantles, so that the radiation of heat from the mantles is not in any point affected by the air passing through, and the whole of the heat generated within 60 the chimney is utilized for rendering the mantle more perfectly incandescent, more especially its top 14, which requires a greater draft, this heat being more thoroughly utilized than when a separate chimney is employed for each mantle, as has hitherto usually been the case in lamps of this kind.

The gallery 7 is provided with an outer row of apertures 15, Fig. 2, and also with a central opening 16. The circular openings 17 indicate the points at which the burners proper are attached. Air enters through the openings 15 and passes over the outer side of the mantles, and as the velocity of the air entering at these points leaves no time for it to become distributed in such a manner that it also passes over these parts of the mantles which are in proximity one to the other the central opening 16 is made of such a size that sufficient air may enter through it for this 80 purpose. Other openings 17 through the floor of the gallery receive the casings of the Bunsen burners, which, it will be observed, are grouped around a central point, represented by the mantle-holder 9 and equidistant therefrom.

The gas-regulating-cock nozzle 5 consists of an under part 18, which is firmly screwed upon the gas-conduit. Passages 19 form the outlets, permitting the gas to pass into a chamber which is constituted by a cap 20, screwed upon the part 18. Into the outlet-opening of this cap, which forms the nozzle 21 itself, extends the conical pin 22 of the lower part 18, and by screwing this part more or less home 95 the aperture of the nozzle may be readily varied.

The method of increasing luminosity in accordance with this invention presents the advantage, as compared with other methods, 100 that it obviates any necessity for a special feed-pipe for the production of increased pressure, that Bunsen burners of various capacities may be selected, and that even with

the employment of a plurality of burners the eye is only able to distinguish a single source of light, because the burners, with their mantles, instead of being inclosed in separate 5 chimneys, as has hitherto been usual, are inclosed in a single chimney and can consequently be arranged very close together. The mantles therefore act one upon the other by radiation of their heat, so that the heating 10 effect of the Bunsen burner is more completely utilized and the luminosity is proportionately greater than when separate chimneys are employed.

What I claim as my invention, and desire 15 to secure by Letters Patent, is—

1. The combination in a lamp, of a plurality of Bunsen burners grouped around a central point and each having means for regulating the gas-supply, mantles for the burners, a 20 mantle-holder rising centrally through the group of mantles, a chimney inclosing all of the mantles, a gallery supporting said chimney, an outer series of openings through said 25 gallery to admit air to the outer surfaces of the group of mantles, and a central opening

through said gallery to admit air to the contiguous inner surfaces of the group of mantles.

2. The combination in a lamp of a gas-supply pipe, a distributing-chamber, a plurality of Bunsen burners supplied from said chamber, said burners being grouped around a central point and each having means for regulating the gas-supply, mantles for the burners, mantle-holders for said mantles, a chimney inclosing all of the mantles of such form 35 as to adapt it to the space occupied by the mantles, a gallery supporting said chimney, an outer series of openings through said gallery to admit air to the outer surfaces of the group of mantles and a central opening 40 through said gallery to admit air to the contiguous inner surfaces of the group of mantles.

In testimony whereof I affix my signature in presence of two witnesses.

WILHELM SCHAEFER.
